FISHERMAN'S CHAIR

Glenn L. Batie, Orient, Edmond C. Fuerst, Sr., Lenox, and Virgil U. Speed, Orient, Iowa

Filed Aug. 28, 1959, Ser. No. 57,354

Term of patent 14 years

(Cl. D15—1)

FIG. 1

FIG. 2

FIG. 3FIG. 5FIG. 4FIG. 1 is a perspective front view of our new fisherman's chair, showing the design of the same when opened for use and with fishing rods shown in broken lines for illustration only;

FIG. 2 is a perspective view thereof in closed or folded position;

FIG. 3 is a rear elevational view thereof;

FIG. 4 is a side view thereof when opened for use;

FIG. 5 is a side view of this chair when closed or folded.

We claim:

The ornamental design for a fisherman's chair as shown and described.
